Patented Nov. 14, 1916.

UNITED STATES PATENT OFFICE.

JOSEPH A. ZWIEBEL, OF BURLINGTON, WISCONSIN, ASSIGNOR TO BURLINGTON BRASS WORKS, OF BURLINGTON, WISCONSIN, A CORPORATION OF WISCONSIN.

COCK.

1,204,532.

Specification of Letters Patent. Patented Nov. 14, 1916.

Application filed April 20, 1916. Serial No. 92,341.

To all whom it may concern:

Be it known that I, JOSEPH A. ZWIEBEL, a citizen of the United States, residing at Burlington, in the county of Racine and 5 State of Wisconsin, have invented certain new and useful Improvements in Cocks, of which the following is a specification, reference being had to the accompanying drawing, forming a part thereof.

10 This invention relates more particularly to the construction of cocks or valves for use in connection with milk and other fluids where cleanliness is of prime importance.

The main objects of the invention are to 15 facilitate removing the valve plug from and replacing it in the case, to afford easy access to internal parts of the cock for the purpose of thoroughly cleansing and keeping the same in a sanitary condition; to 20 provide for tightening and loosening the plug in the case for taking up play and preventing leakage and for permitting free movement and removal of the plug; and generally to improve the construction and 25 operation of cocks or valves of this class.

It consists in the construction, arrangement and combination of parts as herein-after particularly described and pointed out in the claims.

30 In the accompanying drawing, like characters designate the same parts in both figures.

Figure 1 is an axial section on the line 1—1, Fig. 2, of a cock embodying the invention; and Fig. 2 is a side elevation of the cock, the plug of the cock being shown in its closed position in both figures.

The cock as shown by the drawing is specially designed for drawing off milk from 40 vats or tanks, but with little or no change, is suitable for other purposes, especially where cleanly and sanitary conditions are important.

The device comprises a case or body *a*, 45 preferably made of non-corrosive metal or alloy, and having a tapering bore open at the ends, and a peripheral flange *b*, adjacent the larger end of the bore, as shown in Fig. 1. The case is also formed with 50 flanged necks *c*, having passages preferably in alignment with each other and intersecting the tapering bore on diametrically opposite sides thereof, as shown in Fig. 2, the flanges serving as coupling members for 55 connecting the cock on one or both sides

with correspondingly flanged pipes. A tapering plug *d*, preferably made like the case, of a non-corrosive metal or alloy, is removably fitted in the tapering bore of the case and is formed, as shown in Fig. 1, with a transverse passage or opening *e* corresponding in size and shape with the passages in the necks *c* and adapted to register therewith and connect the same, forming a continuous passage through the cock, when the plug is turned in the case into a position at right angles from that in which it is shown in Fig. 2.

The plug is provided with an operating handle or arm *f*, which may be attached to its larger end in any convenient manner, but preferably as follows: The plug *d* is formed, as shown by the drawing, with a central square boss or projection *g* at its larger end, on which is removably fitted a square opening in one end of the handle or arm *f*, which is fastened in place by a flanged cap or screw *h*, threaded in a central hole in said boss or projection, and formed with a polygonal wrench head. The circular flange of the cap or screw overhanging the outer end of the square boss or projection engages with the upper or outer side of the handle or arm *f* around the square opening therein, and rigidly confines the handle or arm on said boss or projection.

To save metal and make the cock lighter, the larger end of the plug may be cored, as shown in Fig. 1.

A hook or lug *i*, notched or fitted to engage and work with the flange *b* on the case *a*, has a squared or flattened shank *j*, fitted in a hole through the handle or arm *f*, parallel with the axis of the plug *d*. A wing nut *k* threaded on the reduced end of the shank *j*, secures the hook or lug *i* to the handle or arm *f*, and to the plug *d*, and serves to adjust the plug axially in the case or to tighten and loosen the same therein, for taking up wear or play and preventing leakage, also for locking the plug in any desired position, or for loosening and permitting its free movement therein and its removal therefrom.

The plug *d* may be detached and withdrawn axially from the case *a* by removing the nut *k* from the threaded shank of the hook or lug *i*, but to facilitate the removal of the plug, the flange *b* is formed as shown

in Fig. 2, with a notch *l*, through which the hook or lug *i* may be withdrawn with the handle or arm *f* and the plug, without removing the nut *k*, or disconnecting the handle or arm from the hook or lug.

According to the preferred practice in the operation of the device, the hook or lug *i* is not detached from the handle *f* to release and remove the plug from the case for 10 cleansing the cock, but the handle or arm is turned from its normal closed position in which it is shown in Fig. 2, counterclockwise to the position indicated by the dotted line *m*, in which position the hook or lug *i* is 15 directly opposite the notch *l* and may be instantly withdrawn with the handle and plug from the case. When the plug is thus removed from the case, it as well as the case and its connections, can be easily and thoroughly cleansed. The plug is replaced in 20 the case by a reversal of the operations above mentioned, the nut *k* being tightened to take up play between the plug *d* and case *a*, to produce a working fit between them, 25 or lock the plug in any desired position.

In the normal movement of the plug *d* and its operating handle *f* through an arc of ninety degrees, for opening and closing the cock, the hook or lug *i* is not brought 30 into register with the notch *l*, thereby accidentally releasing the plug and permitting its axial displacement in the case.

As shown in Fig. 2, the cock is opened by turning the handle *f* clockwise downward 35 into a vertical position, and is closed by turning it back to the horizontal position in which it is shown.

Various modifications in minor details of construction and arrangement of parts may 40 be made without departing from the principle and scope of the invention as defined in the following claims, as, for example, the necks *c* of the case or body *a* may be threaded or provided with other coupling means for 45 connecting it with a vat, tank or the like, or with one or more pipe sections.

I claim:

1. In a cock the combination of a case having a tapered bore open at the ends and a 50 peripheral flange notched adjacent the larger end of the bore, a tapered plug removably fitted in said bore, and a hook detachably adjustably connected with the plug and adapted by engagement with said flange to 55 confine the plug in the case.

2. In a cock the combination of a case having a tapered bore open at the ends and a

peripheral notched flange adjacent the larger end of the bore, a tapered plug removably fitted in said bore, and a hook connected 60 with the plug and adapted by engagement with the flange to hold the plug in place in the case within the range of movement normal for opening and closing the cock, but when turned into normal position opposite the notch in the flange to permit instant removal of the plug from the case in its normal open and closed positions and by its adjustment to take up wear and play between the plug and case.

3. In a cock the combination of a case having a tapered bore open at the ends and a peripheral flange adjacent the larger end of the bore, a tapered plug removably fitted in said bore, and a hook connected with said 75 plug and adapted by engagement with said flange to hold the plug in place in the case, the hook being adjustable axially relative to the plug and adapted to take up play between the plug and case and to lock the plug 80 in different angular positions.

4. In a cock the combination of a case having a tapered bore open at the ends and a notched peripheral flange adjacent the larger end of the bore, a tapered plug removably fitted in the case, and a hook adjustably connected with the plug and adapted by engagement with said flange to hold the plug in place in the case within the range of movement for opening and closing the 90 cock, but when turned into abnormal position opposite the notch in the flange to permit instant removal of the plug from the case, the adjustment of the hook relative to the plug serving to tighten or loosen the 95 plug in the case.

5. In a cock the combination of a case having a tapered bore open at the ends and a peripheral flange adjacent the larger end of the bore, a tapered plug removably fitted 100 in said bore and provided at the larger end with a handle arm, a hook adapted to engage with said flange to hold the plug in place in the case and having a threaded shank fitted in a hole in the handle arm 105 parallel with the axis of the plug and provided with a nut for taking up play between the plug and case.

In witness whereof I hereunto affix my signature in presence of two witnesses.

JOSEPH A. ZWIEBEL.

Witnesses:

FRANK A. GEER,
SIMON J. MADDEN.
